CONTROL REGISTER FOR AIR CONDITIONING APPARATUS

Stanley Hart, Berlin, Conn., assignor to Tuttle & Bailey, Inc., New Britain, Conn., a corporation of Connecticut

Application June 28, 1934, Serial No. 732,758

4 Claims. (Cl. 98—101)

The present invention relates to a register for controlling the admission of cold or refrigerated air, for example, from a conditioning unit to the room to be conditioned.

5 The aim of the present invention is to provide an improved register whereby the velocity, volume and deflection of conditioned air admitted into the room may be very nicely controlled, objectionable drafts and currents within the room 10 are eliminated or at least reduced to a minimum, and the air conditioning unit may be made smaller.

With a register constructed in accordance with the present invention, the incoming air is effectively and thoroughly mixed with and brought to the temperature of the room air in such manner that objectionable drafts are eliminated, and a higher velocity of the injected air and a greater initial difference between the temperatures of the room air and the injected air may be had, thus permitting the use of a smaller air conditioning unit.

Other objects will be in part obvious and in part pointed out more in detail hereinafter.

25 The invention accordingly consists in the features of construction, combination of elements and arrangement of parts which will be exemplified in the construction hereinafter set forth and the scope of the application of which will 30 be indicated in the appended claims.

In the accompanying drawings, wherein I have shown, for illustrative purposes, several embodiments which the present invention may take,

Fig. 1 is a front view of the register;

35 Fig. 2 is a cross sectional view showing, more or less diagrammatically, the arrangement of baffles and deflectors, the baffles being shown as fully opened and in central position;

Fig. 3 is a view similar to Fig. 2 but illustrating 40 the manner in which the incoming air may be deflected to one side;

Fig. 4 is a similar view showing the register closed;

Fig. 5 is a view similar to Fig. 2 but showing 45 a slightly different embodiment;

Fig. 6 is a transverse sectional view taken substantially on line 6—6 and illustrating a practical embodiment of the invention;

50 Fig. 7 is a front view of the register illustrated in Fig. 6 with the front frame and the fixed deflectors removed and clearly illustrating the operating mechanisms for adjusting the movable baffles; and

Fig. 8 is a sectional view taken substantially on 55 line 8—8 of Fig. 7.

In accordance with the present invention, the register is provided with a plurality of baffles arranged to provide a plurality of streams of air associated in sets or pairs, the streams of each set or pair being caused to meet with turbulence 5 a substantial distance in front of the register in such manner as to result in decided aspiration of the room air, the baffles being relatively adjustable so as to control the velocity and volume and also to proportion the amount of air 10 passing through the slots of each pair or set and thereby controlling the direction of deflection of the incoming air into the room. In the present illustrative disclosures, the register has baffles 10 movable with respect to fixed baffles 11, 15 the latter being termed, for the purpose of convenience, as fixed deflectors. It is to be understood that this arrangement is shown by way of illustration only as the deflectors may be adjustable relative to the baffles and any suitable 20 means may be provided for relatively adjusting the deflectors and baffles. The deflectors are interposed between adjacent baffles. The opposing sides of the baffles and deflectors are similarly inclined to the plane of the register so that the 25 slots between the several members are inclined. The slots, at opposite sides of each baffle, are inclined towards each other, and the slots are spaced apart so that the streams of air, after they have passed through the register, will meet 30 in advance of the front face of the register.

In the present illustrative disclosures, the deflectors are of generally triangular shape with one apex extending rearwardly to a position between adjacent baffles 10. The walls 12 of each 35 baffle are inclined correspondingly to the inclination of the opposing side walls of the deflectors. The front face 12' of each baffle is relatively wide. In effect, the baffles are in the form of truncated triangles positioned reversely to the deflectors. 40 The slots of the several pairs between the deflectors and the baffles are designated by the numerals 13, 14, and 15. It will be observed that the forward portions of the slots of each pair are spaced apart by the width of the front face 12' 45 of a baffle, and the slots of each pair are inclined towards each other so that the streams passing through the slots will meet at a substantial distance in front of the register. As will be seen from Figs. 2, 3, and 5, the streams of each and 50 the front face 12' of the intervening baffle define a more or less triangular space, one in front of each baffle, and the room air is drawn into these spaces and mixed with the injected air. With this arrangement, there will be a considerable 55

turbulence along the lines at which the several streams meet, and a high degree of aspiration of the room air is had so that the room air is drawn into the injected air and thoroughly mixed and 5 then dispersed throughout the room without objectionable drafts.

The velocity and volume with which the incoming air is discharged into the room may be controlled by moving the movable baffles at right 10 angles to the general plane of the fixed deflectors to thereby change the combined areas of the slots, and the direction in which the air is discharged into the room may be very nicely controlled by moving the baffles laterally with respect to the 15 deflectors. In the embodiment shown in Fig. 2, the register is shown in full open position and with the baffles in central position so that the air is discharged directly forwardly, while in Fig. 3 the baffles are shown as adjusted so as to deflect the air to one side. Obviously, the air can 20 be deflected to either side to the desired degree by properly adjusting the baffles. In Fig. 4, the register is shown closed. In Fig. 5 is shown an arrangement similar to what is shown in Figs. 2 and 25 3, but in this case, the rear walls of the baffles are curved so as to give a stream line effect.

I have shown, by way of example, in Figs. 6, 7, and 8, practical arrangements which may be employed for adjusting the baffles, it being understood 30 that this disclosure is by way of illustration only as the specific means for adjusting the baffles are unimportant and other arrangements than those shown may be employed. Referring to these figures, the register is shown as having a 35 flanged frame 28 for supporting the operating parts of the register and a face frame 16 telescoping on the back frame 28. The deflectors 11, which may be made of sheet metal, may be secured to the face frame in any suitable manner, 40 as by means of welding, for example. The movable baffles (which also, by preference, are formed of sheet metal) are secured at their opposite ends to angle irons 17 from which project spaced pins 18. At the opposite ends of the movable 45 baffles are slidable angle irons 19 provided with slots 20 through which the pins 18 extend, these slots being at right angles to the length of the members 19 and the plane of the register. The angle irons 19 are adjusted lengthwise in unison 50 by a right and left hand screw 21 suitably journaled in a bracket 22 and associated with the respective members 19 by links 23 and levers 24. Carried by the screw 21 is a worm wheel 25 with 55 which meshes a worm 26, the forward polygonal end 27 of which extends forwardly through the face frame so that it may be manually turned by means of a socket wrench or the like. The mechanism just described is employed for adjusting the baffle members in the plane of the register so 60 as to change the relative sizes of the slots of each pair and thereby control the deflection of the air.

For the purpose of moving the baffle members at right angles to the plane of the register and thereby change the aggregate area of the slots 65 and thus control the velocity and volume of the incoming air, the following operating mechanism may be employed. The numerals 30 designate channel irons located adjacent opposite ends of the baffles. One web of each of these irons is 70 provided with slots 31 disposed at right angles to and adapted to intersect the previously described slots 20. These channel irons are supported for movement forwardly and backwardly by means of links 32, one end of each link being pivoted to 75 the flange of the back frame and the other end

of each link being pivotally connected to a web of the channel iron. The channel irons are adapted to be adjusted by means similar to that illustrated for adjusting the angle irons 19. As shown in Fig. 7, the channel irons are connected 5 to levers 33 and links 34 to a right and left hand screw 35 adapted to be turned through a worm wheel 36 and a worm 37. From the foregoing description, it will be seen that, when it is desired 10 to adjust the movable baffles to obtain the desired deflection of air, the screw 21 is turned whereby the angle irons 19 are moved longitudinally. When this is done, the side edges of the slots 20 engage the pins 18 and cause these pins to move, the pins being guided in their movements by the 15 edges of the slots 31. When it is desired to adjust the combined area of the slots, and thus control the velocity or volume of the air, the screw 35 is turned, thereby causing swinging movement of the channel irons 30. When these irons are 20 swung, they advance or retreat, as the case may be, from the front of the register, and the edges of the slots 31 cause the pins 18 to move in the direction of the length of the slots 20, the edges 25 of the latter slots then guiding the pins.

As many changes could be made in the above construction and many apparently widely different embodiments of this invention could be made without departing from the scope thereof, it is intended that all matter contained in the above 30 description or shown in the accompanying drawings shall be interpreted as illustrative and not in a limiting sense.

It is also to be understood that the language used in the following claims is intended to cover 35 all of the generic and specific features of the invention herein described and all statements of the scope of the invention which, as a matter of language, might be said to fall therebetween.

I claim as my invention:

1. In a control register of the character described, a register having a front face and a set of laterally spaced members rearwardly thereof, a second set of relatively adjustable members respectively located between the members of the 45 first set and positioned generally in side by side spaced alternating relation to the members of said first mentioned set and rearwardly of said face and forming a plurality of pairs of slots, the slots of each pair being spaced apart by one of 50 said adjustable members and converging towards each other as they progress towards the front of the register so as to cause the streams of air to meet along lines spaced in advance of the front face of the register.

2. In a register of the character described, a set of spaced apart parallel baffle members, and a second set of baffle members respectively interposed between the members of said first set, the members of one set being adjustable relative to 60 those of the other set, the opposite side faces of the members of one set being convergent with respect to the front of the register, and the opposite side faces of the other set being divergent with respect to the front of the register, whereby a 65 plurality of pairs of slots are provided between the baffle members, slots of each pair being convergently spaced apart so that streams of air passing therethrough will be directed towards each other and caused to meet forwardly of and 70 in spaced relation to the front of the register.

3. In a register of the character described, a plurality of spaced apart parallel deflectors the opposite side walls of which are inclined away 75 from each other towards the front of the register,

and baffle members interposed between said deflector members and having their side walls inclined towards each other towards the front of the register, there being slots between the opposed walls of the deflectors and baffle members, said slots being arranged in pairs and the slots of each pair being inclined towards each other so that the streams passing therethrough will meet in front of the register and in spaced relation thereto.

4. In a register of the character described, a plurality of spaced apart parallel deflectors the opposite side walls of which are inclined away from each other towards the front of the register, 15 baffle members interposed between said deflectors

and each having a front wall of substantial width, said baffle members having their side walls inclined towards each other towards the front of the register, there being slots between the opposed walls of the deflectors and baffle members, said 5 slots being arranged in pairs and the slots of each pair being inclined towards each other so that the streams passing therethrough will meet at an appreciable distance in front of the register, and means for adjusting one set of said members 10 relative to the other set so as to vary the total area of the slots and the relative proportions thereof.

STANLEY HART. 15
